UNITED STATES PATENT OFFICE.

GEORGE E. WARREN, OF SWAMPSOCOTT, MASSACHUSETTS, ASSIGNOR TO UNITED SHOE MACHINERY CORPORATION, OF PATERSON, NEW JERSEY, A CORPORATION OF NEW JERSEY.

MANUFACTURE OF SHOES.

Application filed January 12, 1922. Serial No. 528,642.

This invention relates to shoes and methods of making them, being concerned more especially with the heel-portions and finding an application of great utility in connection with the attachment of rubber lifts, or half heels, upon heel-bases secured to the heel-seat-portions of shoes. The usual manner of connecting the elements of this portion of a shoe is first, after lasting the upper over the insole and attaching thereto the outsole at the fore-part, to secure the heel-seat by driving in succession with a loose nailer a series of nails about the edge of this portion, through the outsole, the lasted-over upper, the flange of the inserted counter and the insole. Then the heel-base is nailed upon a heelng machine through the outsole and insole at points between the edges of the upper and counter. Finally, by another heelng machine, or at least by an independent operation, the rubber lift is fixed in place by nails driven into the base. Thus it will be seen that three distinct operations are performed in securing the heel and heel-seat elements. An object of my invention is to simplify such a procedure as just outlined, and to produce a shoe, at the heel-portion of which fewer fastenings are used, without sacrificing strength or impairing the appearance of the product. This I accomplish by simultaneously securing the heel base to the heel-seat-portion and the elements of the upper at said heel-seat to one another, as by driving a line of fastenings which will connect, through a single operation, these portions of a shoe. This having been done, a top-lift, as of rubber, is fixed in place upon the base by a single additional operation, as by driving fastenings through the lift into the base. If desired, these fastenings may be of such a character and so applied that they will enter the heel-seat-portion of the shoe and add to the strength with which the elements are held together. At the same time, means may be produced to locate another shoe-portion, as by forming projections upon the outer surface of the base, preferably by driving nails to project beyond said surface, these projections being arranged to enter depressions in the applied lift. Since this locating means bears a predetermined relation to the shoe and is independent of the position of the base, the applied lift similarly is definitely located, re-

gardless of irregularities in the periphery of the base or the angle at which it is applied.

A machine by which my improved method may be carried out and the heel-portion of a shoe resulting therefrom are illustrated in the accompanying drawing, in which

Fig. 1 shows in front elevation a heelng machine arranged for the performance of the present method;

Fig. 2 is a perspective view of the heel-portion of a shoe prior to the securing of the heel-seat, and with a heel or heel-base associated therewith in preparation for attachment;

Fig. 3 is a similar view, the parts in section, after the nailing of the base and heel-seat;

Fig. 4 illustrates in a like manner the completed heel with a rubber lift attached;

Fig. 5 shows similarly another application of my invention;

Fig. 6 is a perspective view of the heel-portion of my improved shoe provided with lift-locating means, the lift being separated from the base;

Fig. 7 is a like view of a completed heel embodying the feature of Fig. 6; and

Fig. 8 illustrates another form of the lift-locating arrangement.

At 10, in Fig. 2, appears the heel-seat and counter-portion of a shoe-upper, having within it a counter 12 and carrying an insole 14 and an outsole 16, the upper and the overhanging flange of the counter being secured to the insole in lasting by tacks 18. The heel-element 20 is here shown as a base, which is to bear an additional outer lift, as is indicated in Fig. 4. For the attachment of the heel, the workman may mount the shoe carried by its last 22 upon the jack 24 of any suitable heelng machine, that illustrated in Fig. 1 being the well-known Lightning heelng. In this, the jack is movably mounted upon a frame 26, being arranged to press the work by a cam mechanism (not shown) against the die-block 28 fixed in horizontal position upon the frame. Above the die-block reciprocates the top girt 30 carrying drivers 32, arranged to contact with and force into a heel presented to them nails contained in openings 34 in the die-block. A holder 36 is mounted to oscillate beneath the die-block across the openings 34, this having clamps to retain for successive pres-

entation to the heel-seat of the jacked shoe a heel-base and a top-lift. Nails 38, of such length that they will pass through the heel-base and the various overlying elements of the heel-seat and will clinch upon the last-plate, are supplied to the openings 34, as by means of loader mechanism 39. The machine is then actuated, and the drivers descending carry the nails from the openings 10 through the base 20, the outsole 16, the turned-over materials of the upper 10, the flange of the counter 12 and the insole 14, and bend over or clinch them, as is indicated at 37. This line of fastenings welds firmly 15 together all these heel, sole and heel-seat-elements, being inserted near enough to the periphery of the heel to hold the rand crease against gaping. The base and heel-seat having been thus secured and the jack and 20 drivers returned to their normal positions, the holder 36 is swung to bring the lift 40 of rubber or other resilient material over the outer surface of the base, this lift having loaded into its openings 41 nails 42 ready 25 for driving. The drivers having been changed to correspond to this nailing, a second actuation of the machine causes them to strike the nails, so that they pass through the substance of the rubber lift beneath the 30 openings and into the heel-base, their heads coming in contact with the usual washers 43 or like member or members molded into the rubber. At this time the points 44 of the nails 42 may have passed through the base and entered the heel-seat-portion of the shoe, as is illustrated in Fig. 4, thus aiding in holding the parts of the heel-seat together. Preferably the nails are of such 35 length that these points 44 do not emerge 40 at the inner surface of the insole, so that when a new lift is applied in repairing the shoe, said insole is not mutilated by the tearing off of the old lift. If, however, it is desired to obtain greater strength in cer- 45 tain types of heel construction, nails 42 may be employed long enough to clinch over the insole.

Simultaneously with the driving of the 50 nails 38 which furnish the base-attaching group adjacent to the periphery of said base, with their heads flush with the outer surface of the base, another inner group of nails 60 (Figs. 6 and 7) may be driven into the base by drivers 62 (Fig. 1) shorter than the associated drivers 32 which operate upon the 55 nails 38. These shorter drivers 62 leave the nails projecting beyond the base-surface, they preferably being arranged at separated 60 points along its longitudinal axis, two of them being here illustrated. Since the location of these nails 60 is determined by the 65 position of the jacked shoe and the drivers and die-block-openings 34, they will bear a definite angular relation to the heel-seat of the shoe, and will be unaffected by the po-

sition of the base thereon. Heel bases, particularly those to which rubber lifts are applied, are large and irregular, so that the periphery gives little or no indication of how the lift should be placed upon them. 70 With the present invention, the lift may have formed in it means for co-operating with these locating projections, as depressions 64 so molded in the rubber of the lift, at such points that when they are placed over the 75 projections, the lift will be symmetrical with respect to the counter-portion of the shoe. Such being the case, the form of the base is of no consequence in the lift-applying operation, and said base may thereafter be 80 trimmed to the margin of the lift, this latter serving as a gage.

It will be obvious that instead of forming 85 projections upon the base, locating depressions might be produced by the employment of awls longer than the drivers 32 which operate upon the base-attaching nails. Such depressions are illustrated at 66 in Fig. 8 of the drawings. In this case, the lift will have 90 upon its inner face projections 68 to enter the depressions.

In Fig. 5 appears an application of the invention, in which a short or three-quarter 95 outsole 50, instead of one of full length, is used, the heel-base 20' being placed with its inner face directly in contact with the lasted-over edge of the upper. The side of the heel toward the breast, however, may project over the rear edge of the outsole, as is indicated at 52. In this case, the simultaneous 100 base and heel-seat-nailing is done from within the shoe, the nails 54 passing through the insole, edges of the counter and upper and into the base, being clinched at 56 upon the outer surface of said base. The forward 105 nails 58 may also enter the edge of the outsole 50 to secure this portion in place. The rubber lift 40 is attached by the nails 42, as has already been described.

From my improved method of procedure 110 there results a shoe in which the heel-seat-elements, including the insole, counter, upper material and outsole, together with the heel or heel-base, are joined firmly and retentively, and in such a manner as to produce a tight rand-crease, with but a single group of fastenings, while only two such groups complete the formation of the heel. At the same time, the top-lift is accurately located 115 with respect to the shoe.

Having described my invention, what I 120 claim as new and desire to secure by Letters Patent of the United States is:—

1. That method of making shoes which 125 consists in attaching the forepart of an outsole to a lasted shoe, applying a heel base to the unattached heel end of the outsole in proper position relative to the counter portion of the shoe, and then securing both the heel base and the unattached heel end of the 130

outsole to the heel portion of the lasted shoe by a single group of fastenings.

2. That method of making shoes which consists in attaching the forepart of an outsole to a lasted shoe, applying a heel base to the unattached heel end of the outsole in proper position relative to the counter portion of the shoe, securing both the heel base and the unattached heel end of the outsole to the heel portion of the lasted shoe by a single group of fastenings, and completing the heel by attaching a rubber lift by another group of fastenings.

3. The method of making shoes, which consists in applying a heel-base to the heel-seat-portion of a shoe, driving a line of fastenings about the base to simultaneously secure it to the heel-seat and the elements of said heel-seat to one another, applying a resilient lift to the thus-secured base, and driving fastenings through said lift, base and heel-seat.

4. The method of making shoes, which consists in applying a heel-base to the heel-seat-portion of a shoe carrying an insole and outsole and including a counter, driving fastenings through the base, outsole, upper material, counter and insole, applying a rubber lift to the base, and driving fastenings through the lift into the heel-seat.

5. The method of making shoes, which consists in simultaneously securing a portion of a shoe thereto and producing locating means on said portion, and associating with the shoe an element thereof formed with means to engage the locating means.

6. The method of making shoes, which consists in simultaneously securing a heel-portion to a shoe and producing locating means, and associating with the shoe a heel-portion formed with means to engage the locating means.

7. The method of making shoes, which consists in securing a heel-base to a shoe, producing upon such secured base locating means for a heel-lift, said locating means bearing a definite relation to the shoe, and applying a lift to the base in a position determined by the locating means.

8. The method of making shoes, which consists in securing a heel-base to a shoe, and producing upon such base locating means for a heel-lift, said locating means bearing a predetermined relation to the heel-seat of the shoe independently of the position of the base thereon.

9. The method of making shoes, which consists in securing a heel-base to a shoe,

simultaneously producing upon such base locating means for a heel-lift, said locating means bearing a definite relation to the heel-seat of the shoe independently of the position of the base thereon, and bringing into registration with the locating means upon the base locating means upon a lift.

10. The method of making shoes, which consists in simultaneously securing a heel-base upon a shoe and producing upon the base locating projections, and applying to the base a lift having openings to receive the projections.

11. A shoe comprising an upper, a sole associated therewith, a heel-base contacting with the heel-seat, fastenings extending through the base and heel-seat, a resilient lift carried by the base, and fastenings extending through the lift and base through the heel-seat elements.

12. A shoe comprising an upper, a counter, an insole and an outsole, a heel-base contacting with the outsole at the heel-seat, nails extending through the base, outsole, upper material, counter and insole, a rubber lift carried by the base, and nails extending through the lift into the heel-seat.

13. A shoe comprising a heel-base having lift-locating means bearing a predetermined relation to the heel-seat of the shoe, and a lift provided with means for co-operation with the locating means.

14. A shoe comprising a heel-base having a plurality of lift-locating projections bearing a predetermined relation to the heel-seat of the shoe independently of the position of the base thereon, and a lift provided with depressions to receive the projections.

15. A shoe comprising a heel-base, an outer group of nails securing the base to the shoe near the periphery of said base, an inner group of locating nails projecting beyond the outer surface of the base, a lift having openings to receive the locating nails, and an intermediate group of nails securing the lift to the base.

16. The method of making shoes which consists in applying a heel-base to the heel-seat-portion of the upper of a shoe, simultaneously securing the heel-base to the heel-seat, the elements of said heel-seat to one another and producing locating means upon the heel-base, and associating with the heel an element provided with means to engage the locating means.

In testimony whereof I have signed my name to this specification.

GEORGE E. WARREN.
